CLAIM

The ornamental design for a packaged unit for brushes, as shown and described.

DESCRIPTION

FIG. 1 is a bottom perspective view of a packaged unit for brushes showing our new design;

FIG. 2 is an enlarged top plan view thereof;

FIG. 3 is a left side elevational view thereof, the right side being a mirror image;

FIG. 4 is an end elevational view as seen from the bottom of FIG. 2; and,

FIG. 5 is an elevational view of the opposite end thereof. The bristles are partially shown in FIGS. 4 and 5 for ease of illustration.
